Matthew W. Mitchell(57) **CLAIM**

The ornamental design for a shovel handle, as shown and described.

DESCRIPTION

FIG. 1 is a front perspective view of the shovel handle of the present invention;

FIG. 2 is back view of the shovel handle of FIG. 1;

FIG. 3 is front view of the shovel handle of FIG. 1;

FIG. 4 is a right side view of the shovel handle of FIG. 1;

FIG. 5 is a left side view of the shovel handle of FIG. 1;

FIG. 6 is a bottom view of the shovel handle of FIG. 1;

FIG. 7 is a top view of the shovel handle of FIG. 1; and,

FIG. 8 is an environmental perspective view of the shovel handle.

The broken line showing of the shovel in FIG. 8 represent the environment of the claimed design and forms no part thereof.
